Ms. 139

William Savery New York
Sitter's Patent No. 239 dated Oct. 9. 1849.
The schedule referred to in these letters, includes and
mentioning parts of this name.
To all whom it may concern. Be it known that I

I

Res. 239

William Savery of the City, County, and State of New York
have invented or produced a new and ornamental design
for an Air Tight Parlour Stove, embracing a variety of
new and ornamental figures and mouldings in com-
bination on said Stove; and I do hereby declare the
following to be a full and exact description of the same,
reference being had to the annexed drawings forming
a part of this specification.

Figure "No. 1" represents the bottom plates, and figure
"No. 2" represents the top plates of said Stove.

What I claim, and wish to secure by letters patent as
original with me, is the arrangement and combination
of the several original ornamental figures and mouldings
upon this particular Stove Design, as herein described,
and as represented in the annexed drawings.
